AUTOMATIC LOOM

Evariste E. Talbot, Fall River, Mass., assignor of
one-half to Jean B. Daudelin, Fall River, Mass.

Application August 28, 1933, Serial No. 687,069

26 Claims. (Cl. 139—259)

This invention relates to automatic shuttle threading mechanism adapted for use on looms of the automatic weft replenishing type.

In such a loom, a feeler periodically enters the 5 shuttle box at the feeler end of the loom and feels for the filling on the bobbin of the active shuttle as it enters said box. When the filling on the bobbin of said active shuttle is exhausted or substantially exhausted, the feeler sets into operation 10 an automatic weft replenishing mechanism at the replenishing end of the loom which mechanism, without stopping the loom, causes the empty bobbin to be expelled from the active shuttle and replaced by a full bobbin when the shuttle reaches the shuttle box at the replenishing end of 15 the loom and is boxed therein.

The replenishing operation is instantaneous or practically so, the full bobbin being substituted for the empty bobbin while the active shuttle is boxed 20 in the shuttle box at the replenishing end of the loom and the filling on such full bobbin being automatically threaded through the eye of the boxed shuttle at this moment.

In conjunction with such automatic loom, and 25 as an additional safety adjunct to the operation thereof, there is also provided a filling stop motion, usually referred to as the "filling fork". The purpose of the filling fork is to stop the loom automatically in the event that there is no filling 30 on the bobbin or that such filling has become broken between the shuttle and the warp threads.

Both the feeler and the filling fork are operatively connected independently of one another to the starting rod of the loom. Each is capable of 35 independently initiating the operation of the filling replenishing mechanism whenever occasion arises. The filling fork, additionally, is capable of again initiating the operation of the filling-replenishing mechanism in the event that said 40 mechanism fails to place a new supply of filling in the shuttle to replace that broken or exhausted.

Heretofore the shuttle has been equipped with a 45 mechanical threader, usually in the form of a metallic casting provided with threading slots so arranged as to guide the loose end of the filling on the new bobbin through the shuttle eye, and thus automatically thread the shuttle whenever a new bobbin is inserted therein.

The mechanical threader, however, is not entirely reliable in action, and, where as sometimes 50 happens such threader fails to thread the filling on the replacement bobbin through the shuttle at the instant of bobbin change, imperfect weaving 55 results.

To the end, therefore, of providing an automatic shuttle threader applicable to any of the several standard makes of automatic looms, which will be entirely positive in action, I have 60 devised my present invention.

According to my concept, I avoid the necessity for using the metallic threader now commonly employed in all automatic loom shuttles.

Instead, I provide a suction threading mechanism, the operation of which is so timed to the action of the loom parts which initiate the operation of the filling-replenishing mechanism as positively to suck the filling on the replacement bobbin through the threading eye of the boxed shuttle at the moment of bobbin change. 10

In conjunction with and as an adjunct to my novel suction threader I provide a cutter which likewise is so timed to the operation of the loom parts which initiate the operation of the filling-replenishing mechanism that the new filling is 15 automatically severed between the new bobbin and the end-holder of the bobbin hopper at the moment of bobbin change so that the end of such new filling may be sucked into the shuttle and threaded through the threading eye thereof by 20 my novel suction threader.

I realize, of course, that in the early days of the weaving art, it was usual for the weaver, by mouth suction, to thread a shuttle. This, of course, was before the invention of the automatic loom, and 25 would be impossible with an automatic loom where the loom is not stopped to permit threading. Similarly, with those portable suction devices of the early art which were supposed to be worn by the weaver as a belt or harness equipment and applied to the shuttle of the stopped loom. 30

My concept is based on the maintenance of a source of suction which is continually available but which is not applied to the threading eye of 35 the shuttle until such time as the feeler or the filling fork of the automatic loom has operated to initiate the operation of the bobbin changing mechanism.

At this time a normally closed valve controlling 40 the suction is automatically opened and suction is applied to the threading eye of the shuttle when it reaches the shuttle box at the replenishing end of the loom.

Speaking generally, the suction is given to the 45 shuttle by and during the operation of the bobbin changing mechanism.

At the same time, or substantially so, the new filling on the new bobbin is severed. The suction is continued until the end of the filling on the 50 new bobbin has been positively threaded through the threading eye of the active shuttle.

In such threading action the suction positively draws such severed end through the shuttle eye. It also draws the severed or waste end of the filling away from the selvage so as not to become entangled therein or in the shuttle, such waste end being preferably carried down into the suction line and thus entirely out of the weaving room. 55

The suction through the port 45 is for the purpose of threading the shuttle. The suction through the ports 46 and 47 is for the purpose of carrying off the waste through the suction lines 5 as soon as cut off by the temple cutter. Thereafter the suction control valve is automatically restored to closed position in readiness to repeat its operation whenever a condition of empty bobbin is again registered by the feeler or filling 10 fork.

The cutter is preferably in the form of a pair of scissors so disposed with reference to the end-holder of the bobbin magazine as to cut the filling on the new bobbin which is in readiness to be inserted into the active shuttle as a replacement when the bobbin changing mechanism operates. One of the blades of the scissors is fixed and the other blade is movable by and during the movement of the bobbin changing mechanism itself. 15 The movable blade operates to sever the filling on the new bobbin just prior to the moment that the new bobbin is actually inserted into the shuttle so that the end of the new filling may be caught by the suction and drawn into the threading eye of the shuttle when the shuttle reaches the shuttle box at the replenishment end of the loom and is boxed therein.

For the purposes of this application I have illustrated my invention as applied to a standard 30 Draper automatic loom. This treatment is purely illustrative and in no way limiting, however, since the principles of my invention apply to other standard makes of automatic loom without substantial modification and reorganization, and 35 regardless of whether the bobbin hoppers of such looms are of the rotary type or of other well known type.

In the drawings:

Fig. 1 is a somewhat schematic view of an automatic loom equipped with an automatic suction 40 threader in accordance with my invention, the loom being seen from the front.

Fig. 1a is a fragmentary end elevation of Fig. 1.

Fig. 2 is an end elevation of the suction control valve and the push and pull pawls for actuating the same.

Fig. 3 is a side elevation of said valve.

Fig. 4 is a section on the line 4—4 of Fig. 3.

Fig. 5 is a face view at the suction outlet side 50 of the valve, particularly showing the fixed port thereof.

Fig. 6 is a cross-section through the valve body, particularly showing the rotary valve plug and its series of ports which register successively with 55 the fixed port.

Fig. 7 is a longitudinal section through the valve assembly.

Fig. 8 is a stripped view illustrating the co-action 60 of the push and pull pawls and the valve ratchet, and

Figs. 9 to 15 inclusive are timing diagrams of the valve.

I have indicated at 10 a fragmentary part of the breast beam of an automatic loom of standard 65 manufacture, at 11 the lay of the loom, at 12 and 13 the usual shuttle boxes disposed respectively at the feeler and the replenishing end of the loom frame, and at S the shuttle. The hopper or magazine for the filled bobbins B is indicated at 14, and the usual end-holder for the filling ends F 70 of such bobbins is indicated at 15.

The loom is equipped with the usual feeler 16. This is of standard type and is adapted to feel through the slot of the shuttle box 12 at the 75 feeler end of the loom and through the slot of the

active shuttle S when boxed in said box to determine whether or not the filling on the bobbin in said shuttle is critically exhausted and requires replenishment.

The loom is also equipped with the usual filling-stop motion, indicated generally at 17, for initiating the operation of the bobbin-changing mechanism whenever the filling on such bobbin is broken between the shuttle and the warp threads or for causing said mechanism to repeat 10 its operation in the event that it has failed to place a new supply of filling in the shuttle to replace that broken or exhausted.

Both the feeler 16 and the filling stop motion, or more accurately the so-called "filling fork" 15 thereof are operatively connected by the usual connections indicated generally at 18 and 19, respectively, to one end of the usual change shaft or starting rod 20 of the loom. The opposite end of the starting rod 20 is connected with the weft 20 replenishing mechanism of the loom by means of the usual operating connections.

Such replenishing mechanism and the operating connections therefore are of usual construction and need only be briefly described.

In brief, there extends from the hopper stand 14 an arm or dead shaft 21 on which is mounted the usual bobbin transperrer 22 for transferring a fresh supply of filling (i. e. a new bobbin B) to the shuttle when boxed in the shuttle box 13. 30 Normally the transperrer is maintained in inoperative position by means of the spring 23. Extending downwardly from the transperrer is an arm 24. Pivotally connected to said arm is a dog 25, the free end of which is adapted to be engaged by the bunter of the lay, as usual, whenever filling replenishment is called for.

Extending rearwardly from the starting rod 20 is the usual rocker arm 26, spring tensioned as at 27. The arm 26 through the usual connections partly shown in dotted lines in Fig. 1 and generally indicated by the reference numerals 28 and 29, operate the transperrer 22 whenever filling replenishment is called for.

When a bobbin change is called for, the starting rod 20 is rocked, and through the motion-transmitting connections just indicated, sets the bobbin change mechanism into operation. The lowermost bobbin in the bobbin magazine is pushed downwardly into the shuttle when the shuttle reaches the shuttle box 13 and is boxed therein, the contact of the new bobbin with the empty bobbin in the shuttle pushing the empty bobbin through the bottom of the shuttle and the filled bobbin into its correct position within the 55 shuttle.

At the same time or substantially so, the end F of the filling on such bobbin, which end is supported in the end holder 15, is severed, so that the new filling may be threaded into the shuttle eye. 60 The suction is continued for the time of complete action of the port 45 which is for the purpose of threading in through the eye of the active shuttle.

In accordance with my invention suction is 65 utilized to positively thread the new filling through the threading eye of the shuttle now boxed in the box 13, the arrangement being such that the suction is not applied to the shuttle box 13 and the filling-end cutter is not caused to operate until 70 after the feeler 16 and/or filling fork 17 has initiated the operation of the bobbin change mechanism itself. In other words, both the suction control, here shown as a rotary valve, and the filling end cutter, operate in timed relation to the op- 75

eration of the bobbin change mechanism. Both valve and cutter, as here shown, take their operation from the starting rod 20 which rod is itself operated by either the feeler 16 or filling fork 17 whenever bobbin change is called for.

The motion transmitting connections between the starting rod and the suction control valve, and the general installation as to such valve and the suction supply and delivery connections there-
10 of are shown in Figs. 1 and 2.

Referring first to Fig. 1 I have indicated at 30 a suction supply pipe. This is connected with any suitable source of vacuum not shown and may conveniently be brought through the floor
15 of the weaving room as shown in Fig. 1.

The suction is under the control of a rotatable valve indicated generally at 31 in Fig. 1. The suction pipe 30 enters the casing of this valve and suction is applied to the shuttle box front 13
20 at certain times through the branch pipe 32. The suction control valve is normally closed but is opened whenever the starting rod 20 is actuated. This permits the suction in pipe 30 to draw upon shuttle box front 13 through pipe 32.

25 Before proceeding to a detailed description of the valve, I might note that the motion transmitting connections from the starting rod to the valve include a rocker arm 33 linked as at 34 to the rocker arm 26 of the starting rod. The arm 33 is fast on one end of a rock shaft 35 journaled in suitable bearings on the loom frame and provided at its opposite end with a rocker arm 36 carrying a pull pawl 37 adapted to coact with a ratchet wheel 38 fast on the shaft 39 of the port-
30 ed valve plug or core 40, (Fig. 7). Also coacting with said ratchet wheel is a push pawl 41 eccentrically mounted as at 42 on a constantly rotating shaft 43 which takes its drive from some constantly rotating part of the loom.

40 The push pawl 41 is rotated continuously by shaft 43. Normally this pawl idles on the long tooth 44 of the ratchet 38, which as shown here has seven short teeth and one long tooth.

Whenever filling replenishment is called for
45 and the starting rod 20 rocked, the rocking motion of this shaft is transmitted by the motion transmitting connections 26, 34, 33, 35, 36 to the pull pawl 37. Said pawl thereupon effectively engages the short tooth of the ratchet on which

50 it happens to rest and turns the ratchet far enough ahead (in the counter-clockwise direction of Fig. 4) for the push pawl 41 to engage with the back of the short tooth immediately ahead of the long tooth on which it had theretofore been idling. This engagement of the push pawl rotates the ratchet tooth by tooth through one complete revolution and until the long tooth 44 is again brought under the push pawl, whereupon the push pawl again idles on said tooth until the starting rod 20 is again actuated to initiate another operation of the bobbin change mechanism.

During the rotation of the ratchet and with it the ported plug or disc 40 of the valve, suction draft is established through opening of the port 45 to suction line 32 and shuttle box front 13 from the suction pipe 30 through the valve to the pipe 32 and shuttle box 13.

This suction connection is intermittent, however, in the sense that the valve plug or disc 40 has a plurality (here shown as three) of valve ports 45, 46, 47, with intervening blocking areas 48, 49 and 50 (Fig. 6). While the ratchet is being intermittently rotated through one complete revolution, these ports are adapted to register suc-

cessively with a fixed port 51 (Fig. 5) in a fixed plate or end closure 52 of the valve casing. The suction pipe 30 delivers into the valve chamber 53 behind the ported plug or disc 40 and the branch pipe 32 connects with the fixed port 51 so that when any of the ports 45, 46 or 47 are registered with the port 51, a suction connection is established to the shuttle box 13 and when any of the port-blocking areas 48, 49 and 50 are in registry with said port 51, the suction connection to 10 said shuttle box 13 is broken.

The purpose of the port 45 is to produce suction when the shuttle is in the box 13. The port 46 is to produce suction to draw the waste thread cut by the temple cutter when the shuttle is in 15 the box 12. The port 47 is to produce the same action as the port 46 only on the second later pick with the shuttle in the box 12. Should the temple cutter have failed to cut the waste filling in due time for the port 46 when in action, the 20 port 47 would have a chance to pick up the failure of the port 46 for both the ports 46 and 47. The shuttle would be in the opposite box 12.

This result is best attained with the triple ported valve shown particularly where the ports 25 46 and 47 are of equal area and the port 45 of double the area of either port 46 or 47.

Considering the timing diagrams, Figs. 9 to 15, these show the various positions of the rotary valve disc 40 with respect to the fixed port 51 30 during one complete step by step rotation of the valve.

Fig. 10 corresponds to the pawl position of Fig. 8. The valve has been rotated counter-clockwise the distance of one ratchet tooth to bring port 45 35 into registry with port 51 and establish the suction circuit to the shuttle box front 13. The port 45 is wide enough to still register with the port 51 on the next movement of the ratchet one tooth space (Fig. 11), and thus in a properly proportioned apparatus to afford a time factor equivalent to practically two picks of the shuttle during which the suction circuit is established to the shuttle box front 13.

This allows enough time for the shuttle which 45 was in the shuttle box 13 to have been thrown across to the shuttle box 12 and before it has fully returned to box 13.

On the next rotation of the valve one ratchet tooth space (Fig. 12) the blocking area 50 covers 50 fixed port 51 and the suction circuit is broken.

It is immediately reestablished, however, on the rotation of the valve the next tooth space (see Fig. 13) which brings port 46 into registry with port 51.

55 This port, and also port 47, are only wide enough to remain in registry with port 51 while the shuttle is making one pick, as from box 13 to box 12 in Fig. 13 or from box 12 to box 13 in Fig. 15, there being an intermediate interval of suction 60 discontinuance represented in Fig. 14 wherein the further rotation of the valve one tooth space has brought blocking area 49 over port 51.

In addition to their function as suction ports, the openings 51 and 45, 46 and 47 also act as 65 thread cutters. The suction when applied draws the end F of the new filling, after it has been severed at a point between the bobbin magazine and the end holder 15, through the shuttle eye to thread the shuttle. Any loose end of such filling cut off beyond the shuttle eye after the shuttle has been threaded is sucked through the branch pipe 32 and into the valve casing. The fixed port 51 acts as the fixed element of a cutter constituted by the end plate 52 and the several 75

ports of the rotary valve disc 40, the thread in the registering ports being cut by the relative movement of the valve disc to the fixed end plate 52, and the cut portions being drawn down into the suction pipe 30 and out of the weaving room.

In order to increase the efficiency of this cutting action, the back edges of the several ports 45, 46, 47 may be slightly beveled or sharpened, as indicated at 53¹, Fig. 6. Thus the cutter chops the loose thread drawn through it into small lengths which will not clog the valve.

In order to avoid back-lash of the ratchet wheel, I provide a friction check therefor. This may conveniently take the form of a friction wheel 54 fast on the ratchet shaft 39 having half circle notches corresponding to each tooth of the ratchet and a friction roller 55 operating against the corrugated or otherwise roughened periphery of said wheel. The friction roller 55 is rotatably journaled in the bifurcated lower end of a stem 56 which stem is loosely mounted in suitable bearings 57 on the valve casting for yielding movement relative to the friction wheel 54. Confined about said stem between the upper bearing and a shoulder 58 formed on the stem is a coil spring 59, the function of which is to constantly urge the friction roller against the wheel.

In order to permit setting of the shaft 39 and thus of the ratchet wheel 38 to meet any given loom conditions, said shaft is extended beyond the valve casting as a threaded stem 60. On this is mounted an adjustment collar 61 and a lock nut 62. Between the collar 61 and the shaft bearing at the adjacent end of the valve casting is confined a coil spring 63.

The purpose of the spring on the shaft 39 is to produce a varied tension on the shearing blade edge of the ports 45, 46, 47 on the rotary valve 48 in order to form a firm shearing contact with

40 sharp edge of the port 51 against the steel plate 52. As previously indicated, I provide a cutter operating in timed relation to the bobbin-change mechanism to cut the end F of the new filling on the bobbin which is in position to be thrust down 45 into the shuttle boxed in box 13. This cutter severs the new filling between the bobbin and the end-holder 15 so that when filling replenishment is called for and suction established to the box 13, such end will be free to be sucked into and 50 through the threading eye of the shuttle boxed in said box.

As here shown, such cutter comprises a pair of scissors (Fig. 1) which is so mounted as to cut the successive filling ends F at a point between the 55 bobbin magazine and the end holder 15 as the bobbins are successively presented thereto.

One blade of the scissors here shown as the upper blade 65, is fixed and the other blade 66 is movable relative to the fixed blade to produce the 60 cutting action. The scissors may be mounted in the relation indicated in any convenient manner and may be operated from any convenient part of the bobbin changing mechanism.

Conveniently, the loop end of the fixed blade 65 65 may be extended as a strap 67 the free end of which is loosely sleeved over the dead shaft 21.

The loop end of the movable blade 66 has an arm 68 which is connected to an arm 69 at one end of a lever 70 supported on the loom in any suitable manner, as by suspending it loosely as at 71 from the dead shaft 21. The opposite end of lever 70 has an arm 72 pivoted on the same pivot pin 73 which pivotally connects the parts 24 and 25 so that said lever is swung by and in the movement 75 of said parts.

Thus, whenever the bobbin change mechanism is actuated, the movable blade 66 is caused to close upon the fixed blade 65 and cut the interposed filling end F. The blade 66 is restored to original position upon return of the bobbin change mechanism and particularly the parts 24 and 25 to original position.

As usual in automatic looms, the empty bobbin when ejected from the shuttle in box 13 falls by gravity down the guide 74 into the empty bobbin receptacle 75.

The suction connection 32 to the box 13 may enter said box at any desired point, either at top, side or bottom, and preferably enters it adjacent that end of the shuttle box at which the threading eye of the shuttle will be positioned when the shuttle comes to rest within the box.

Various modifications in structure, arrangement and methodical operation may obviously be resorted to within the spirit and scope of my invention as defined by the appended claims.

What I therefore claim and desire to secure by Letters Patent is:—

1. In the art of threading the shuttle of a loom equipped with automatic bobbin changing mechanism and with an operating part which initiates the operation of such bobbin changing mechanism, said shuttle being devoid of the usual automatic threader and threading slots of the usual self-threading loom shuttle but having a threading eye extending from the shuttle throat through a wall of the shuttle to atmosphere, the method which consists in automatically creating within the shuttle box at the replenishing end of the loom simultaneously with the initiation of the bobbin changing operation and without stopping the loom a suction effective to draw the end of the new filling through the threading eye of the shuttle while the shuttle is still boxed in said shuttle box.

2. In the art of threading the shuttle of a loom equipped with automatic bobbin changing mechanism and with an operating part which initiates the operation of such bobbin changing mechanism, said shuttle being devoid of the usual automatic threader and threading slots of the usual self-threading loom shuttle but having a threading eye extending from the shuttle throat through a wall of the shuttle to atmosphere, the method which consists in automatically severing the end of the filling on the replacement bobbin simultaneously with the initiation of the bobbin changing operation, and in automatically creating within the shuttle box at the replenishing end of the loom simultaneously with the initiation of such bobbin changing operation and without stopping the loom a suction effective to draw the end of the new filling through the threading eye of the shuttle while the shuttle is still boxed in said shuttle box.

3. In a loom equipped with automatic bobbin replenishing mechanism, the combination with an operating part which initiates the operation of such bobbin replenishing mechanism and a shuttle devoid of the usual automatic threader and threading slots of the usual self-threading loom shuttle but having a threading eye extending from the shuttle throat through a wall of the shuttle to atmosphere, of an automatic shuttle threading mechanism operated by and in the movement of said part which initiates the operation of the bobbin changing mechanism and effective to positively thread the free end of the new filling on the replacement bobbin through said threading eye of the shuttle whenever a bobbin change occurs.

4. In a loom equipped with automatic bobbin replenishing mechanism, the combination with

- an operating part which initiates the operation of such bobbin replenishing mechanism and a shuttle devoid of the usual automatic threader and threading slots of the usual self-threading loom 5 shuttle but having a threading eye extending from the shuttle throat through a wall of the shuttle to atmosphere and said means including, means for automatically creating within the shuttle box at the replenishing end of the loom 10 whenever said operating part initiates the operation of the bobbin changing mechanism a suction effective to positively thread the end of the new filling through the threading eye of the shuttle while the shuttle is still boxed in said shuttle 15 box and without stopping the loom.
5. In a loom equipped with automatic bobbin replenishing mechanism, the combination with an operating part which initiates the operation of such bobbin replenishing mechanism and a shuttle devoid of the usual automatic threader and threading slots of the usual self-threading loom shuttle but having a threading eye extending from the shuttle throat through a wall of the shuttle to atmosphere and said means including, 20 a normally closed suction control valve automatically opened whenever said operating part initiates the operation of the bobbin changing mechanism, and a suction connection from said valve to the shuttle box at the replenishing end 25 of the loom effective when said valve is open to create a suction in said box and positively thread the end of the new filling through the threading eye of the shuttle while the shuttle is still boxed in said box and without stopping the loom.
- 30 6. In a loom equipped with automatic bobbin replenishing mechanism, the combination with an operating part which initiates the operation of such bobbin replenishing mechanism, a suction connection to the shuttle box at the replenishing end 35 of the loom, a normally closed valve controlling said suction connection, a normally idle mechanism for said valve, and operative connections between said actuating connections and the part which initiates the operation of the bobbin changing mechanism effective whenever a change of bobbin is necessary to cause said valve to open and establish a suction through said suction connection capable of drawing the end 40 of the new filling through the threading eye of the shuttle boxed in said shuttle box.
- 45 7. Apparatus as claimed in claim 6 wherein the valve is a rotatable valve which is rotated step by step through one complete revolution whenever a change of bobbin occurs.
- 50 8. Apparatus as claimed in claim 6 wherein the valve is a rotatable valve which is rotatable step by step through one complete revolution whenever a change of bobbin occurs and wherein also the valve actuating mechanism includes a ratchet associated with the valve and a push pawl and a pull pawl cooperative with said ratchet.
- 55 9. The combination in an automatic loom having automatic bobbin replenishing mechanism and having an operating part which initiates the operation of said bobbin replenishing mechanism whenever a change of bobbin is necessary, of a suction connection to the shuttle box at the replenishing end of the loom, a normally closed 60 valve controlling the suction through said connection, and operative connections between said valve and said loom part which initiates the operation of the bobbin replenishing mechanism effective whenever a change of bobbin is necessary to open said valve and create a suction
- through said suction connection within the shuttle box at the replenishing end of the loom whereby the filling of the new bobbin inserted in the shuttle when boxed in said box is positively sucked through the threading eye of such shuttle. 5
10. An automatic loom as claimed in claim 9 wherein there is also provided a filling end cutter operated by and in the operation of the bobbin changing mechanism to sever the end of the filling on the new bobbin which is in readiness to be inserted into the shuttle when the shuttle is boxed in the shuttle box at the replenishing end of the loom. 10
11. The combination in an automatic loom having bobbin replenishing mechanism and having a part which initiates the operation of such bobbin replenishing mechanism through the usual starting rod of the loom whenever a change of bobbin is necessary, of a suction connection to the shuttle box at the replenishing end of the loom, a normally closed valve controlling the suction through said connection, a ratchet associated with said valve and having a long tooth and a plurality of shorter teeth, a continuously 15 rotating shaft having a push pawl eccentrically mounted thereon and normally idling on the long tooth of said ratchet, a pull pawl disposed for engagement with the ratchet, and operative connections from said pull pawl to said starting rod such that when the starting rod is actuated by the part which initiates the operation of the bobbin changing mechanism said pull pawl will rotate the ratchet sufficiently to clear the push pawl from the long tooth thereof and the ratchet will thereafter be rotated step by step through 20 a complete revolution by the push pawl to periodically establish and break the suction circuit through said suction connection. 25
12. Apparatus as claimed in claim 11 wherein there is also provided a filling end cutter operated whenever the starting rod is actuated and effective to sever the end of the filling on the new bobbin which is in readiness to be inserted into the shuttle. 30
13. In a loom, a suction connection to a shuttle box thereof, a normally closed valve controlling the suction through said connection, a ratchet associated with said valve and having a long tooth and a plurality of shorter teeth, a continuously 35 rotating shaft having a push pawl eccentrically mounted thereon and normally idling on the long tooth of said ratchet, a pull pawl disposed for engagement with the ratchet, and means whereby said pull pawl may be caused to rotate the ratchet sufficiently to clear the push pawl from the long tooth thereof so that the ratchet may thereafter be rotated step by step through a complete revolution by the push pawl to periodically establish and break the suction circuit through said suction connection. 40
14. In an automatic loom, the combination with shuttle boxes, automatic bobbin changing mechanism adjacent one of said shuttle boxes, a starting rod operatively connected with said bobbin changing mechanism, and a part operatively connected with said starting rod and adapted to initiate the operation of said bobbin changing mechanism whenever a change of bobbin is necessary, of a continuously rotating driven shaft, a push pawl eccentrically mounted 45 thereon, a rotatable suction control valve having a ratchet adapted to be engaged by said push pawl, a suction connection through said valve to the shuttle box at the replenishing end of the loom, a pull pawl cooperative with said ratchet, 50
- 70
- 75

and operative connections from said pull pawl to said starting rod.

15. Apparatus as claimed in claim 14 wherein there is also provided a filling end cutter operated whenever the starting rod is actuated and effective to sever the end of the filling on the new bobbin which is in readiness to be inserted into the shuttle.

16. An automatic loom as claimed in claim 14 wherein the valve construction includes a fixed part having a port therein opening into the suction connection to said shuttle box, and a rotatable plug having a plurality of ports therein successively registerable with said fixed port to alternately establish and break the suction connection to said shuttle box during rotation of the valve.

17. In an automatic loom, the combination with shuttle boxes, an automatic bobbin changing mechanism mounted adjacent one of said shuttle boxes, a starting rod operatively connected with said bobbin changing mechanism, and a part operatively connected to said rod and adapted to initiate the operation of said bobbin changing mechanism whenever a change of bobbin is necessary, of a suction connection to the shuttle box at the replenishing end of the loom including a normally closed control valve, and means actuated by and in the actuation of said starting rod to open said valve whenever a change of bobbin is necessary.

18. An automatic loom as claimed in claim 17 wherein the valve opening means includes a continuously rotating shaft, a push pawl eccentrically mounted on said shaft, a ratchet associated with said valve and disposed normally to be idly engaged by said push pawl, a pull pawl also disposed for coaction with said ratchet, and operative connections from said pull pawl to said starting rod effective upon actuation of said starting rod to rotate said ratchet into a position wherein it may be thereafter effectively engaged by said push pawl and rotated step by step through a complete revolution during which revolution the suction connection to said shuttle box at the replenishing end of the loom is periodically established and broken.

19. In an automatic loom having automatic bobbin replenishing mechanism and having a shuttle box at the replenishing end of the loom, a shuttle adapted to be boxed in said shuttle box for bobbin replenishment, said shuttle having a threading eye extending from the shuttle throat through a wall of the shuttle to atmosphere but being devoid of the usual automatic threader and threading slots of the usual self-threading loom shuttle, and means timed to the operation of the bobbin replenishing mechanism and operating whenever said replenishing mechanism operates for positively threading the free end of the new filling on the replacement bobbin through said threading eye of the shuttle while the shuttle is still boxed for bobbin replenishment in said shuttle box at the replenishing end of the loom.

20. A loom attachment as claimed in claim 19 wherein pneumatic means is employed to thread the shuttle.

21. A loom attachment as claimed in claim 19 wherein suction means is employed to thread the shuttle.

22. In an automatic loom having automatic

bobbin replenishing mechanism and having a shuttle box at the replenishing end of the loom, a shuttle adapted to be boxed in said shuttle box for bobbin replenishment, said shuttle having a threading eye extending from the shuttle throat through a wall of the shuttle to atmosphere but being devoid of the usual automatic threader and threading slots of the usual self-threading loom shuttle, a suction connection leading into said shuttle box and normally unsupplied with suction, and means timed to the operation of the bobbin replenishing mechanism for supplying suction to said suction connection whenever said replenishing mechanism operates whereby to positively thread the free end of the new filling on the replacement bobbin through said threading eye of the shuttle while the shuttle is still boxed for bobbin replenishment in said shuttle box at the replenishing end of the loom.

23. A loom attachment as claimed in claim 22, wherein the suction connection to the shuttle box terminates adjacent to the position within the shuttle box occupied by the suction threading eye of the shuttle boxed in said shuttle box at the replenishing end of the loom.

24. A loom attachment as claimed in claim 22, wherein a filling end cutter is mounted adjacent the replenishing end of the loom and is so timed with the operation of the bobbin replenishment mechanism as to sever the end of the new filling on the replacement bobbin whenever said replenishing mechanism operates.

25. The combination in an automatic loom having automatic bobbin replenishing mechanism and a shuttle box at the replenishing end of the loom, of a shuttle adapted to be boxed in said shuttle box for bobbin replenishment, said shuttle having a threading eye extending from the shuttle throat through a wall of the shuttle to atmosphere but being devoid of the usual automatic threader and threading slots of the usual self-threading loom shuttle, and suction means timed to the operation of the bobbin replenishing mechanism for automatically threading the free end of the new filling on the replacement bobbin through said threading eye of the shuttle while said shuttle is still boxed for bobbin replenishment in said shuttle box at the replenishing end of the loom.

26. The combination in an automatic loom having automatic bobbin replenishing mechanism and a shuttle box at the replenishing end of the loom, of a shuttle adapted to be boxed in said shuttle box for bobbin replenishment, said shuttle having a threading eye extending from the shuttle throat through a wall of the shuttle to atmosphere but being devoid of the usual automatic threader and threading slots of the usual self-threading loom shuttle, suction means timed to the operation of the bobbin replenishing mechanism for automatically threading the free end of the new filling on the replacement bobbin through said threading eye of the shuttle while said shuttle is still boxed for bobbin replenishment in said shuttle box at the replenishing end of the loom, and a filling end cutter mounted adjacent the replenishing end of the loom and so timed to the operation of the bobbin replenishing mechanism as to sever the end of the new filling on the replacement bobbin whenever said replenishing mechanism operates.

EVARISTE E. TALBOT.
